UNITED STATES PATENT OFFICE.

HENRY E. WAITE AND SAMUEL H. BARTLETT, OF NEW YORK, N. Y.

MAGNETO-TELEPHONE.

SPECIFICATION forming part of Letters Patent No. 316,205, dated April 21, 1885.

Application filed August 28, 1884. (No model.)

To all whom it may concern:

Be it known that we, HENRY E. WAITE and SAMUEL H. BARTLETT, citizens of the United States, residing in the city, county, 5 and State of New York, have invented certain new and useful Improvements in Magneto-Telephones, of which the following is a specification.

Our invention relates to magneto-telephones; 10 and it consists in certain improvements in the construction thereof, as more particularly pointed out hereinafter.

In the drawings, Figure 1 is a perspective view of an ordinary box telephone-transmitter and our receiver hanging therefrom. Fig. 15 2 is a plan view of the telephone-receiver with the handle removed; and Fig. 3 is a sectional view, the parts of the case being separated.

Heretofore it has been common to attach 20 the connecting conducting-cord to binding-posts on the transmitter and receiver. We have arranged the terminals of the conducting-cord so that they will pass directly through holes in the transmitter-box and be suitably 25 secured to the circuit-wires, and the other terminals will enter holes in the receiver case and box connected to the terminals of the magnet-coil.

The ends of the wires, both of the conductor 30 A and coil B, are easily and firmly secured between the metal plates or buttons a b by suitable screws, and in order to prevent the strain of the weight of the telephone from pulling the ends out from between the plates 35 or disks we provide a washer or plate, C, which is adjusted to bear against the covered ends of the conductor and bite or clamp them in the holes in the case, and an eye-screw, D, is passed through the case and serves to hold 40 the plate C in position. By this means a very secure fastening is provided for the terminals of the conductor, and the weight of the telephone will be supported upon the covered ends of the conductor, instead of the naked 45 wire in the connecting buttons or plates. In some instances we attach a cord, E, to the eye-screw to relieve the conductor of the weight of the telephone, the other end being connected to the transmitter-case or other place.

50 In this receiver the case is made of three sections—the body portion F, containing the operative parts of the telephone, a detachable

mouth or ear-piece, G, having a shoulder supporting the diaphragm, and a detachable rear handle-piece, H.

The magnet I is preferably made in the form shown—that is, semicircular—with a re-entering end to which is secured a soft-iron core, J, having a coil, B. The magnet is supported upon a shoulder, f, of the body F. Also supported upon the shoulder f is a spring-arm, K, bent in the manner shown, and adapted to bear upon the diaphragm L. If the diaphragm is of magnetic material the spring need not necessarily be so, as it simply serves to strain the diaphragm; but we prefer to make the diaphragm of wood, cork, card-board, or other non-magnetic material, and make the spring of magnetic material. An adjusting-screw, k, is provided, which passes through the spring 7 at the elevated portion and into the material of the case.

By this arrangement all the parts are very compactly arranged, and when the handle part of the case is removed the operative parts 7 are all exposed for inspection and adjustment.

We have found a telephone constructed as above set forth to be very simple and cheap to manufacture, and at the same time very effective and convenient to use.

What we claim is—

1. The combination, with a telephone-case having holes, of a conducting-cord the terminals of which pass through the case, a clamp or plate adapted to bite or press the ends of the conductor against the sides of the holes, and a screw for holding said clamp, substantially as described.

2. The combination, with the telephone-case, of a magnet supported upon a shoulder in the body part and carrying a coil or helix connected to line, and a spring-arm of magnetic material, also secured to the shoulder and bent so as to bear against the diaphragm, and an adjusting-screw, substantially as described.

In testimony whereof we have signed our names to this specification in the presence of two subscribing witnesses.

HENRY E. WAITE.

SAMUEL H. BARTLETT.
